UNITED STATES PATENT OFFICE.

AMOS F. LANIER, OF WORCESTER, MASSACHUSETTS, ASSIGNOR, BY MESNE ASSIGNMENTS TO HI-LO-JACK COMPANY, A CORPORATION OF MASSACHUSETTS.

JACK.

1,426,201.

Specification of Letters Patent. Patented Aug. 15, 1922.

Application filed June 4, 1920. Serial No. 386,519.

To all whom it may concern:

Be it known that I, AMOS F. LANIER, a citizen of the United States, residing at Worcester, in the county of Worcester and State 5 of Massachusetts, have invented a new and useful Jack, of which the following is a specification.

This invention relates to a jack of the "lazy tongs" type.

10 The principal objects of the invention are to provide a convenient and comparatively inexpensive stabilizing device that will effectively prevent the rocking of the jack in either direction endwise, and restrict all 15 tendency toward such action; to provide it in such form that it can be assembled readily and inexpensively; and to provide improvements in the details of construction by which these advantages are secured.

20 Reference is to be had to the accompanying drawings, in which

Fig. 1 is a side view of a jack constructed in accordance with this invention;

Fig. 2 is a plan;

25 Fig. 3 is a horizontal sectional view on the line 3—3 of Fig. 1 on enlarged scale; and

Fig. 4 is an enlarged front view of one bearing and its support.

This invention, as stated, relates to that 30 type of jack in which the principle of the "lazy tongs" is employed, and more specifically to that type in which gear teeth, or some equivalent thereof, are used at the meeting ends of the arms to prevent the rocking 35 of the jack and cause the arms on both sides to work absolutely in unison independently of the location of the load on strain. These jacks have proved very practical in operation, having a wide range of motion and a 40 strong construction and high lifting power.

The invention is shown in a form comprising a base 10 near one end of which is mounted a bracket 11 and near the center of which is mounted a corresponding bracket 12. 45 These brackets are shown as riveted to the base. It will be noted that the base 10 extends beyond the support for the jack which consists of the brackets 11 and 12. This extension is on one side only and on the right 50 hand side looking at it from the direction in which power is applied as will appear. This is to prevent the rocking over of the jack sidewise when turning the crank to lift a heavy load.

55 These two brackets 11 and 12 constitute opposite walls, each provided with two cir-

cular recesses 13 cut all the way through them and with vertical slots 14 narrower than these recesses and extending down from the top edges of these brackets centrally into 60 them. This is an important feature of the invention for it provides for a quick and convenient assembly of the parts and the permitting of the making of the two brackets 11 and 12 relatively fixed on the base 65 before the rest of the device is assembled.

It is to be noted that there is a ring 15 in each of the recesses 13 and that the cylindrical end of a square shaft 15 extends into each of these rings. Each of these shafts 16 70 is shown as provided with a square portion on which is a gear segment 17 preferably integral, but permissibly mounted on it by means of a square hole through the gear. These gear segments can be formed integral 75 with the shaft in each case if desired or otherwise fixed firmly thereon. One advantage of this invention lies in the fact that only two pairs of gear segments are required, one at the top and one at the bottom, instead 80 of four pairs as usually has been the case heretofore.

Each of the shafts 15 carries at each end an arm 20. Each arm is provided with a square hole 21 in which the shaft fits and 85 with which it must turn. The gear segments being geared together, the two arms on each side must move together. These parts are duplicated at the top as will be obvious. The two arms 20 on each side are pinned together 90 by pins 22 or the like, and provided with a connection 23 at the extreme ends for an upper pair of arms 24, which are the same as the arms 20 and connected in the same way.

Extending across between the ends of the 95 arms is a double threaded right and left hand screw 25 having a square end 26 for the reception of an extension wrench or crank as is well understood in this art. The two pairs of arms on each side and the opposite ends of the screw are connected together in each case 100 by a nut 28 which has studs 27 projecting from it on which the arms are pivoted.

The stabilizing device at the top is a duplicate of that at the bottom and the parts are connected up by a load support 30 formed of one piece of die-pressed metal and having the recesses 13, slots 14 and rings 15 for the shafts 16 just as is the case at the bottom. The slots and recesses are cut out in the die-pressing operations 110 which the base and load supporting cap are manufactured.

In assembling the device, the base, with the parts 10, 11 and 12, is made or set up in permanent form and the same is true of the work rest 30. The jack itself is then made and assembled outside with the shafts 16 in position with their gears on them and the ends of these shafts are inserted down through the slots 14 which are wide enough to receive them and down into the recesses 13. The same assembly is made at the top. Then the rings 15 are inserted endwise and pressed in with any necessary degree of pressure so that they surround the ends of the shafts and constitute bearings for them. This affords a very material economy in the assembling of the device and assures its being assembled properly without the necessity of any other adjustments or machining operations. I do not herein claim the method of assembling disclosed in this application, but reserve the right to present the subject matter of the same in a divisional application.

Although I have illustrated and described only a single form of the invention I am aware of the fact that modifications can be made therein by any person skilled in the art without departing from the scope of the invention as expressed in the claims.

Therefore I do not wish to be limited to all the details of construction herein shown and described, but what I do claim is:—

1. In a load lifting jack, the combination of a base having openings, shafts located in said openings, bearing members pressed into the openings and carrying the shafts, said base having slots along which the shafts can be moved into the openings in the absence of the bearing members, with a lazy tongs structure carried by said shafts.

2. In a load lifting jack, the combination with a screw and arms constituting a lazy tongs structure, of a structure comprising opposite walls permanently connected together provided with parallel slots having enlargements at their ends, shafts having means for connecting the lazy tongs arms, located in said enlargements and capable of passing through said slots thereto, and bearing members for the shafts fitting in said enlargements and preventing the removal of the shafts.

3. In a load lifting jack, the combination with a set of arms constituting a lazy tongs construction, of opposite walls provided

with slots having enlargements, transverse shafts having means for connecting the lazy tongs arms, their ends being located in said enlargements and capable of passing along said slots thereto, and bearing members for the shafts fitting in said enlargements and preventing the removal of the shafts along the slots.

4. In a load lifting jack, of the lazy tongs type, the combination of four sets of pivotally connected arms and means across the center for connecting two opposite pivots thereof, with two shafts having means for holding the arms fixed to their respective ends, two side walls permanently fixed together each having slots extending in from one edge wide enough to receive the circular ends of the shafts and circular enlargements at their ends, and rings fitting on the ends of the shafts and inserted in said enlargements.

5. In a load lifting jack of the lazy tongs type, the combination of four sets of pivotally connected arms and a screw across the center connecting them, two transverse shafts each having a non-circular cross section, said arms having perforations of the same shape for receiving them so that they are fixed to their respective shafts, the shafts having circular ends, two side walls permanently fixed together each having slots extending in from one edge wide enough to receive the circular ends of the shafts and circular enlargements at their ends, and bearing rings fitting on the ends of the shafts and inserted in said enlargements by forcing them in axially.

6. In a load lifting jack, the combination with a screw and arms constituting a lazy tongs structure, of a base having opposite walls provided with a projection extending beyond the wall on one side to prevent overturning the device when turning the screw, said walls being provided with parallel slots having enlargements at their ends, shafts having means for connecting the lazy tongs arms located in said enlargements and capable of passing through said slots thereto, and bearing members for the shafts fitting in said enlargements and preventing the removal of the shafts.

In testimony whereof I have hereunto affixed my signature.

AMOS F. LANIER.
